UNITED STATES PATENT OFFICE.

ROBERT DELAUNAY-BELLEVILLE, OF ST.-DENIS, FRANCE, ASSIGNOR TO SOCIETE ANONYME DES ETABLISSEMENTS DELAUNAY-BELLEVILLE, OF ST.-DENIS, FRANCE, A CORPORATION OF FRANCE.

CONSTRUCTION OF WATER-TUBE BOILERS.

1,132,458.

Specification of Letters Patent. Patented Mar. 16, 1915.

Application filed July 20, 1914. Serial No. 852,077.

To all whom it may concern:

Be it known that I, ROBERT DELAUNAY-BELLEVILLE, citizen of the French Republic, residing at St.-Denis, Department of the Seine, in France, have invented certain new and useful Improvements in the Construction of Water-Tube Boilers; and I do hereby declare the following to be a full, clear, and exact description of the invention, such as will enable others skilled in the art to which it appertains to make and use the same.

In a multiple coil Belleville boiler element, in which the coils are so arranged that their convolutions are co-axial and each convolution of each coil lies vertically adjacent to a convolution of another coil, it is important to equalize, as far as possible, the vaporization of the several coils. The present invention aims to provide a boiler element so constructed that the above result may be obtained. The invention consists in shortening the lower convolution of the first two coils of the element, so as to uncover or expose a portion of the lower convolution of the second coil and of the third coil, and consequently, increase the vaporization power of these tubes.

It is important, in order to economize space, to arrange the junction boxes above the lowermost tubes in superposed and horizontal relation, as in a single coil element, with the exception of the lower rear boxes of the first and second coils, which are formed as hereinafter described.

The invention is illustrated in the accompanying drawing, in which:—

Figure 1 shows the improved boiler element in side elevation; Fig. 2 is a front elevation of the element showing the lower front box, partly in section, and showing the other front junction boxes superposed in horizontal relation; Fig. 3 is a rear elevation showing the rear boxes superposed in horizontal relation from the lower box of the third coil to the top, the lower rear box of the first coil and that of the second coil being offset; Fig. 4 is a section taken on the line $x-x$ of Fig. 1. Fig. 5 is a side elevation of a modified form of the boiler element shown in Fig. 1.

The coils are designated by the letters A, B, C, the letter V being added to designate the front boxes, and the letter R to designate

the rear boxes. The letters V and R 55 are furnished with indices, which indicate the tier of the boxes reading upwardly.

AV¹, BV¹, CV¹, are the three compartments of the lower front box common to the three coils. The water comes from the feed 60 collector D through a conduit of large cross section d , fills the chamber E, and passes through the adjusted orifices 1, 2, 3, into the compartments AV¹, BV¹, and CV¹, from which the lower tubes of the three coils proceed. The other boxes are superposed in horizontal relation like the boxes of a single coil element. The upper box F also comprises three compartments having independent communication with the upper collector. 65

In each coil, the tubes are designated by a small letter with an index which indicates the tier, starting with the lower tube, which is numbered 1. The tubes of uneven number 75 rise from front to rear; they are shown on the right hand in Fig. 2. The tubes of even number ascend from rear to front; they are on the left of Fig. 2.

At the rear, the support for the boxes is 80 carried to the under side of the box CR¹. The boxes AR¹, BR¹, need no support. All the other rear boxes CR¹, AR², BR², CR² . . . . are superposed in horizontal relation, as in an element with a single coil. 85

The first convolution of the coil A is constituted by the tubes a^1 and a^2 , which are relatively short and by the box AR¹. This box is offset horizontally from right to left, (Fig. 3), to permit of the passage of the 90 tube b^1 of the second coil.

The first convolution of the second coil is constituted by the tubes b^1 , b^2 , which are relatively short, but longer than the tubes a^1 , a^2 of the first convolution. The box BR¹ 95 connects the tubes b^1 , b^2 and completes the convolution. This box is also offset from right to left to permit of the passage of the tube c^1 of the third coil.

The first convolution of the coil C is 100 formed by the rear box CR¹, by the tube c^1 that it receives on the right, and which comes from the compartment CV¹ of the front box and by the tube c^2 which proceeds from the left of the box CR¹ and is connected to the box CV² on the left. 105

In each coil, the circuit is formed from below upward, from box to tube and from

tube to box in the following order, taking the coil C for example; —CV¹—c¹—CR¹—c²—CV²—c³—CR²—c⁴—CV³—c⁵—CR³—c⁶, and the corresponding compartment of the upper box F. All the tubes inclined in the same direction are substantially parallel.

Fig. 5 represents a modification in which the rear boxes of the first convolution of the first and second coils are dispensed with. 10 The tubes a¹ and a², for the first coil, comprise but a single tube a¹, a². The same applies to the tubes b¹ and b² of the second coil. In each of the first two coils, this tube, which itself forms the first convolution, is 15 deflected or offset from right to left in order not to interfere with the passage of the first tube of the coil which is located above; it then ascends and is connected with the box AV² of the first coil, or BV² of the second 20 coil.

What I claim is:—

1. A boiler element composed of a plurality of coils having co-axial convolu-

tions, each convolution of each coil being vertically adjacent to a convolution of another coil and the lower convolution of certain coils being shorter than the lower convolution of the adjacent coil, for the purpose described. 25

2. A boiler element composed of three 30 coils each having a plurality of convolutions arranged in co-axial relation, each convolution of each coil being vertically adjacent to a convolution of another coil and the lower convolution of the second coil being 35 shorter than the lower convolution of the third coil, and the lower convolution of the first coil being shorter than the lower convolution of the second coil, for the purpose 40 described.

In testimony whereof I affix my signature, in presence of two witnesses.
